UNITED STATES PATENT OFFICE.

CHARLES F. SPERY, OF CHICAGO, ILLINOIS, ASSIGNOR TO HOOVEN RADIATOR COMPANY, OF CHICAGO, ILLINOIS, A CORPORATION OF ILLINOIS,

LOCK-SEAMING MACHINE.

1,318,415.

Specification of Letters Patent.

Patented Oct. 14, 1919.

Application filed October 14, 1918. Serial No. 257,935.

To all whom it may concern:

Be it known that I, CHARLES F. SPERY, a citizen of the United States, residing in Chicago, in the county of Cook and State of Illinois, have invented certain new and useful Improvements in Lock-Seaming Machines, of which the following is a specification.

My invention relates to machines for 10 making a lock-joint or seam between sheet metal parts. More particularly it relates to machines for lock-seaming the ends of metal strips used in automobile radiator construction, and for other work in which there is 15 an analogous arrangement of the parts in the neighborhood of the joint.

The principal objects of the invention are to provide a simple, strong and relatively small and cheap device which will rapidly, 20 and in a single operation, produce a lock-joint between such parts. Other objects and advantages will appear hereinafter.

In the accompanying drawings, which form a part of this specification, I have 25 illustrated these improvements in a highly efficient and preferred form. In these drawings—

Figure 1 is a top plan of the machine;

Fig. 2 is a side elevation thereof;

Fig. 3 is an enlarged medial longitudinal section of one end portion of the machine;

Fig. 4 is a front end view of the machine;

Fig. 5 is a fragmentary section showing one of the forming rollers and its adjusting means; and

Figs. 6, 7 and 8 are fragmentary views showing the several successive forming operations.

The machine comprises a frame, base, or 40 main support 10 mounted on legs 11. On the driving shaft 12 is secured the disk 13 having the crank pin 14 to which is connected the pitman 15. Slidably mounted upon the main support 10 and connected to 45 the pitman 15 at 16 is the reciprocating member 17 having a central longitudinal upstanding part surfaced on each side at 18 on lines parallel with the lines of forward and rearward movement of the reciprocating member 17, and provided at 19 with cam surfaces slanting to the surfaces at 20, the latter being less widely spaced apart oppositely than are the surfaces 18. Two levers, each pivoted intermediate its ends, 55 and substantially in the form of bell-crank 22—23, 22—23, are mounted for rocking

movement on the studs 25 respectively, rigidly secured upon the base or main support 10. At the free end of each of the lever arms 22 is secured a roller 26 adapted to travel 60 upon the surfaces 18, 19, 20 of the reciprocating member 17, and at the free end of the lever arms 23 respectively is secured a roller 27 pressing against the jaws 30. These jaws or clamping members 30 are oppositely disposed and are mounted for movement toward and from each other on bars 31 respectively pivoted at 32 to the frame or base 10. Between the jaws 30 is a projecting tongue-like anvil 35 rigidly secured to the 70 frame or base 10 as by bolts 36. The sides of the anvil 35 are made to conform to the work adapted to rest against them (Fig. 4) and the holding faces of the jaws 30 are similarly so formed. Each jaw 30 is provided 75 with a gripping element 37 adjustable by means of the screws 38 whereby the jaws as a whole are effectively adjustable toward and from each other so as to provide the desired strength of grip upon metal of 80 different thicknesses operated upon.

The reciprocating member 17 carries at its forward end a bracket or head 45 in which are mounted two forming wheels or rollers 39 and 40 and an intermediate shoe 85 41. The roller 39 and shoe 41 are grooved to receive the material forming the joint and the roller 40 has a flat face for laying over and pressing down the rib and completing the joint. Each of these rollers 39 90 and 40 is mounted on a shaft 42 (Fig. 5) having an eccentric portion 43 on which the roller rotates. By turning the shaft 42, as by a screwdriver, the roller is moved closer to or farther from the face of the anvil 35. 95 A set screw 44 holds the shaft 42 in any desired position of adjustment. The anvil 35 faces the path of travel of the forming elements 39, 40 and 41, and has an effective length equal to that of the throw of the 100 pitman 15.

Radiator cores of the type herein referred to are formed of a plurality of sections side by side, each section including two strips of sheet metal having their ends secured together. In Figs. 6, 7 and 8, and in Fig. 4, I have shown end portions of one such core section. Various expedients have heretofore been resorted to for seaming such end portions together with various kinds of 105 joints. I find the locking joint herein illustrated to be highly effective, and my ma-

chine for accomplishing the result is notably rapid in operation. This will be more clear from the following description of its mode of operation.

5 Two of the strips 50 and 51 are placed by the operator upon the anvil 35 in the position shown by Fig. 4. Thereupon pressure upon a treadle (not shown) operates the clutch 53 on the driving shaft (which clutch 10 may be of the kind usually employed on punch presses and the like) and the shaft is rotated, driving the reciprocating member 17 forward. In this movement the rollers 26 ride over the inclined cam surface at 19 15 and the jaws are moved toward each other, clamping the work against the anvil 35. So long as the rollers 26 remain upon the surfaces 18 the gripping action is maintained. The forming roller 39 lays the extension 55 20 on one core part down upon the other, or into the position of Fig. 6. The shoe 41, having an inclined groove, next bends the rib over to one side. Following this operation the flat faced roller 40 presses the rib 25 down against the other parts. These operations follow each other closely, and a single stroke of the reciprocating member 17 completes the seam, as shown in Fig. 8. When the reciprocating member 17 moves rear- 30 ward and the rollers 26 are respectively at the cam surface 19, the springs 60 retract the jaws, enabling the operator to remove the work and insert the next two pieces to be operated upon.

35 I claim:

1. In a machine for seaming sheet metal parts, the combination of a main support, a reciprocating member slidably mounted therein, a grooved roller former carried by 40 said reciprocating member, an anvil for the work facing the path of movement of said former, a pair of clamping members oppositely disposed and movably mounted adjacent to said anvil, means operatively associated with said clamping members and with said reciprocating members for moving said clamping members toward said anvil to hold the work thereon, means for maintaining the clamping members in such hold- 45 ing position when the reciprocating member is moving in the forward direction, means for moving the reciprocating member in both directions, and means for withdrawing the clamping members in a direction 50 away from said anvil after the forward stroke of the reciprocating member.

2. In a machine for seaming sheet metal parts, the combination of a main support; a reciprocating member slidably mounted 60 therein, a series of forming elements carried by said reciprocating member, a projecting tongue-like anvil facing the path of movement of said forming elements, a pair

of clamping members oppositely disposed and movably mounted adjacent to said anvil, 65 lever means operatively associated with said clamping members and with said reciprocating member for moving said clamping members toward the anvil to hold the work thereon, means for maintaining the clamping members in such holding position when the reciprocating member is moving in the forward direction, means for moving the reciprocating member in both directions, and means for withdrawing the clamping mem- 70 ber in a direction away from said anvil after the forward stroke of the reciprocating member. 75

3. In a machine for seaming sheet metal parts, the combination of a main support, a reciprocating member slidably mounted therein, a series of forming elements carried by said reciprocating member, a projecting tongue-like anvil for the work facing the path of movement of said forming 80 elements, a pair of clamping members oppositely disposed and movably mounted adjacent to said anvil, a pair of bell-crank levers mounted on the main support and cam surfaces on said reciprocating member for moving said clamping members respectively toward said anvil to hold the work thereon, means including said levers for maintaining the clamping members in such holding position when the reciprocating member is moving in the forward direction, means for moving the reciprocating member in both directions, and means for withdrawing the clamping members in a direction away from 85 said anvil after the forward stroke of the reciprocating member. 90

4. In a seaming machine, the combination with a reciprocating member carrying a forming element, of an anvil facing the path of movement of said forming element, 105 a pair of oppositely disposed jaws respectively mounted to move toward and from said anvil, and means under the control of said reciprocating member for moving the jaws toward the anvil for holding the work 110 thereon.

5. In a seaming machine, the combination with a frame and a reciprocating member carrying a forming element mounted therein, of an anvil facing the path of movement 115 of said forming element, a clamping jaw on each side of said anvil, a lever pivoted intermediate its ends on the frame at each side of said reciprocating member, one end of each lever being in engagement with the reciprocating member, the other end of each lever being in engagement with one of the jaws respectively, and cam means on the reciprocating member for moving the jaws. 120
